UNITED STATES PATENT OFFICE.

NATHAN M. LOWER, OF PITTSBURGH, PENNSYLVANIA, ASSIGNOR TO LOCOMOTIVE STOKER COMPANY, A CORPORATION OF PENNSYLVANIA.

LOCOMOTIVE STOKER.

Application filed January 17, 1925. Serial No. 3,026.

This invention relates to stokers, and more particularly to stokers for locomotives.

One of the objects of the invention is the provision of a mechanical stoker that is provided with new and improved means for selectively operating the fuel delivery vanes or fuel distributing members.

Other objects of the invention are the provision of stoker devices provided with new and improved operating mechanism that is easily manipulated, readily changed from one operative position to another, and one in which the shifting mechanism is safe and that is not likely to become broken or get out of order.

Other and further objects and advantages of the invention will appear from the following description taken in connection with the accompanying drawings, in which Fig. 1 is a vertical section of the rear portion of a locomotive showing the stoker in position thereon, with parts broken away and showing the structure more or less diagrammatically;

Fig. 2 is a section approximately on the lines 2-2 of Figs. 3 and 4 respectively;

Fig. 3 is a section approximately on the lines 3-3 of Figs. 1 and 2 respectively;

Fig. 4 is a section approximately on line 4-4 of Fig. 3, with parts broken away, and showing the structure more or less diagrammatically;

Fig. 5 is an end elevation of the cams and cam operating mechanism on the line 5-5 of Fig. 4, with parts in section and parts broken away;

Fig. 6 is a plan view of a portion of the stoker applied to a locomotive, with parts in section and parts broken away;

Fig. 7 is a section on line 7-7 of Fig. 2;

Fig. 8 is a detail showing the shifter rod; and

Fig. 9 is a developed view of the shifter flanges of the worm wheel.

On the drawings, the reference character 10 designates the back wall of a locomotive firebox 11, and 12 an opening in said wall through which the fuel is adapted to be introduced and distributed over the grates 13.

Since the details of the locomotive constitute no part of the present invention the same are not illustrated and will not be further described.

A distributor plate 14 which extends into

the opening 12 is adapted to receive the fuel 55 from the tender by any suitable means, and from which the fuel is distributed in the firebox by a swinging vane 15 at each side of the distributor plate 14, as is common in the art.

Suitable means are provided for transferring the fuel from the tender to the distributor plate. As shown, a transferring conduit 16 in which the screw conveyor 17 rotates is employed for this purpose. The screw conveyor 17 is operated from the shaft 18 in the usual manner. The shaft 18 is operated from the power shaft 19 through the worm and gear drive 20, the shaft 19 being operated by any suitable power device, as is usual in such constructions.

The fuel from the transferring conduit is delivered to the elevator casing 21 in which reciprocates the plunger or elevator 22 which is raised and lowered by the crank 23 and 75 connecting link 24.

The crank 23 may be provided with a counterweight 230. The crank is operated from the power shaft 19 through the worm 240, gear 25, and intermeshing gears 26 and 27 as clearly shown on Fig. 4 of the drawing.

The elevator or plunger 22 raises the fuel intermittently above and onto the distributor plate 14 from which it is projected into 85 the firebox by the vanes 15 as will presently appear.

The vanes 15 are mounted on shafts to the lower ends of which are secured the gears 250 and 260 which mesh with actuating 90 quadrant gears 270 and 28, respectively, on the upper ends of the vane actuating members 65 and 66. These members comprise sleeves or hubs 67 and 68, to which are rigidly connected the upwardly extending 95 quadrant arms 69 and 70 and the downwardly extending cam engaging arms 29 and 31, respectively. The sleeves or hubs 67 and 68 of the vane actuating members are oscillatably mounted as at 30 and 300. The arms 29 and 31 are operated by actuating cams 32, 33 and 34 which engage the cam engaging members as the rollers 35 and 36 carried by the lower ends of said arms, as will presently appear.

It is desirable at times to trim the fire at one side of the firebox to the exclusion of the other. Suitable means have been provided

for this purpose, which will now be described. In the form of the device selected to illustrate one embodiment of the invention suitable cam members are employed to actuate the vanes. As shown in Fig. 4 the gear wheels 25 and 26 are rigidly secured to the ends of a drum 37 which is suitably mounted on antifriction bearings on the shaft 40 in the casing 38. Slidably mounted on the drum 37 and keyed thereto is a sleeve 39 on the periphery of which are the cam members 32, 33 and 34. The cams 32 and 33 are spaced apart and arranged substantially 180° from the cam 34. In the normal operation of the device the cams 32 and 33 engage the rollers 35 and 36, respectively, for operating the vanes 15.

The cams 32 and 33 are adapted to project the vanes 15 forwardly and the same are retracted by the springs 410 and 420 which are connected to the casing 38 and to arms 430 and 44 on the sleeves or hubs 67 and 68, respectively.

Suitable means are provided for shifting the sleeve longitudinally of the drum 37 so that one of the vanes may operate to the exclusion of the other in order to trim the fire at one side only of the firebox. As shown, pins or bolts 41 secured to the outer end of the sleeve 39 slideably engage openings in the gear wheel 25 and have their outer ends attached to a shifter ring 42 operating in an annular recess in the outer face of said wheel 25. The ring 42 is provided with a flange 43 which is adapted to be engaged by a shifter member 44, see Fig. 3, which is adapted to be operated by the bell crank 45 secured to the shaft 46. The shaft 46 is adapted to be operated by the handle 47. The pins or bolts 41 may, if desired, constitute the sole means for preventing relative rotation between the drum and the sleeve. By means of the lever 47 the operator can cause the vanes to be operated alternately or either one to the exclusion of the other. If, for instance, it is desired to operate the vane at the right to trim the fire at the right hand side of the firebox the lever 47 is operated to move the sleeve 39 outwardly so that the roller 36 of the lever 31 will be in the path of both cams 33 and 34. When the sleeve is in this position, the roller 35 will be engaging the cylindrical portion 48 of the inner end of the sleeve 39 and the spring 410 will hold the left vane in inoperative position. By shifting the sleeve 39 inwardly the left vane may be made to operate in like manner to the exclusion of the right vane, by engaging the cams 32 and 34.

Since the cams 32 and 33 actuate vanes that operate in opposite directions by similar actuating arms, they are of different contour. The contour of the intermediate cam is preferably a mean between the contour of the other two.

In order to prevent shifting of the cams while the same are in engagement with the rollers 35 and 36 suitable means are provided whereby the sleeve 39 can be shifted only during the time the rollers 35 and 36 are engaging the cylindrical portion of the sleeve between the cam surfaces. As shown, the shifter member 44, which may have its shifter ring engaging head in the form of a segment 49, see Fig. 8, is provided with an outwardly extending projection or timer lug 51 which operates in grooves 52 or 53 formed by the flanges 54 and 55 on the inner periphery of the wheel 25. The flange 54 is provided with a notch 56 which is large enough to permit the passage of the timer lug 51 therethrough when the notch comes opposite the said lug to shift the sleeve inwardly. The flange 55 is likewise provided with a similar notch 57 through which the timer lug may pass when the notch comes opposite said lug to shift the sleeve 39 outwardly. The notches 56 and 57 are arranged 180° apart whereby in shifting from either extreme to the central position it is not possible to accidentally shift too far into the other extreme position. In order to insure proper shifting and avoid locking the parts during the shifting operation the timer lug and the edges of the flanges adjacent the notches are tapered as shown at 58 and 59, respectively.

When the cams are in the position shown in Fig. 4, the vanes are both normally operating and the timer lug is engaging the groove between the flanges 54 and 55. When it is desirable or necessary to shift the cams inwardly so as to operate the left vane to the exclusion of the right, the lever 47 is moved rearwardly, which forces the timer lug 51 against the flange 54 and when the notch 56 comes opposite the lug the latter will pass through, thus shifting the sleeve 39 inwardly for operating the left vane, exclusively.

When it is desired to operate the right vane to the exclusion of the left, the lever 47 is moved in the opposite direction for shifting the sleeve 39 outwardly in a manner similar to that described above. The lever 47 is held in adjusted position, as by means of a notched quadrant 60, in the usual manner, see Fig. 6.

It is thought from the foregoing taken in connection with the accompanying drawings that the construction and operation of my device will be apparent to those skilled in the art. Various changes in size, shape, proportion and details of construction may be made without departing from the spirit and scope of the appended claims.

I claim as my invention:

1. In a stoker for locomotives, in combination, a pair of distributing vanes, means for delivering fuel into the path of said vanes, means including cam mechanism for

- operating said vanes for distributing said fuel, and means for adjusting said mechanism for operating one of said vanes to the exclusion of the other.
5. 2. In a locomotive stoker, in combination, a pair of distributing vanes, an elevator for delivering fuel into the path of said vanes, cam operated mechanism for said vanes for throwing the same forwardly in timed relation to the operation of said elevator, and means for controlling the operation of said mechanism for operating said vanes alternatively.
10. 3. In a locomotive stoker, in combination, a pair of swinging vanes, an elevator mechanism for intermittently delivering fuel into the path of said vanes, means including cam mechanism for causing a vane throw after each fuel delivery of said elevator mechanism for distributing said fuel, and means for controlling said cam mechanism for operating either of said vanes to the exclusion of the other.
15. 4. In a locomotive stoker, a pair of distributing vanes, means for delivering fuel into the path of said vanes, a pair of oscillating arms for operating said vanes, a plurality of cams for oscillating said arms, and means for causing one of said cams to operate upon one of said arms and another upon the other arm, respectively, or for causing certain of said cams to operate upon either of said arms to the exclusion of the other.
20. 5. In a locomotive stoker, in combination, a pair of swinging vanes, means including a plunger for delivering fuel into the path of said vanes, an oscillating arm geared to each of said vanes, cams for oscillating said arms for swinging said vanes forwardly to distribute said fuel, and means for causing certain of said cams to operate on one of said arms to the exclusion of the other.
25. 6. In a locomotive stoker, in combination, fuel distributing members, means for delivering fuel into the path of said members, cam operated mechanism for moving said members forwardly in timed relation to the movement of said means for distributing said fuel, and means for varying the order
- of operation of said members relatively to the operation of said means.
7. In a locomotive stoker, in combination, a pair of fuel distributing members, means for delivering fuel into the path of said members, means including cam mechanism for moving said members, and means for controlling said mechanism for operating said members either alternately or one to the exclusion of the other.
10. 8. In a stoker, in combination, a pair of swinging vanes, an elevator for delivering fuel into the path of said vanes, means including cam members for moving said vanes forwardly for distributing said fuel in the firebox of a locomotive, means including a resilient member for retracting said vanes, and means for shifting said cam members from a position for actuating both of said vanes to a position for actuating one only of said vanes.
15. 9. In a stoker, in combination, a pair of swinging vanes, an elevator for delivering fuel into the path of said vanes, arms geared to said vanes for swinging the same, a plurality of rotating cams for operating said arms, means for changing the relative positions of said arms and cams for operating said arms alternately, or one to the exclusion of the other, and means for preventing the changing of the relative position of said cams and arms except at predetermined points in the rotation of said cams.
20. 10. In a stoker, a pair of swinging vanes, means including cam members for moving said vanes forwardly, and means for shifting said cam members to operate one vane to the exclusion of the other.
25. 11. In a locomotive stoker, a pair of distributing members, means for delivering fuel into the path of said members, means for moving said members, rigid means for operating said second-named means for positively moving said members forwardly for distributing said fuel, and means for shifting said rigid means whereby the same will cause the operation of one of said members to the exclusion of the other.

NATHAN M. LOWER.
